UNITED STATES PATENT OFFICE.

JOSEPH H. ADAMS, OF FLATBUSH, NEW YORK, ASSIGNOR TO THE TEXAS COMPANY,
OF HOUSTON, TEXAS, A CORPORATION OF TEXAS.

OIL-CONVERTING APPARATUS FOR THE CONVERSION AND TRANSFORMATION
OF OILS.

Application filed June 25, 1918. Serial No. 241,837.

To all whom it may concern:

Be it known that I, JOSEPH H. ADAMS, a citizen of the United States, residing at Flatbush, in the county of Kings and State 5 of New York, have invented a new and useful Oil-Converting Apparatus for the Conversion and Transformation of Oils, and of which the following is a specification.

This invention relates to the art of converting fluids such as oils into products of dissimilar character, such as for example, the conversion of heavier petroleum oils into gasoline, and has special reference to apparatus for use in this art.

15 The apparatus illustrated and described herein is particularly adapted for use in carrying out my oil converting process for the conversion and transformation of oils set forth and claimed in my co-pending application Serial No. 241,836 filed of even date 20 herewith.

One object of this invention is to provide a relatively simple and inexpensive means of applying super-heated steam under easy 25 control to heated and vaporized oil in mist like or vaporous form for the purpose of altering the physical and chemical characteristics of such oil to a predetermined extent.

30 Another object within the contemplation of this invention is to devise an apparatus which will facilitate the conversion of heavy and high boiling oils such as kerosene, gas oil and other non-viscous and neutral oils as well 35 as those of the coal tar group into lighter oils and oily spirits such as gasolines, naphthas, benzol and toluol; and which will do so under conditions of continuous operation, to eliminate undesirable interruptions 40 and other features common in many types of so-called oil conversion apparatus.

This invention seeks to provide an apparatus well adapted for "cracking" and transforming hydro-carbon and other oils according to my process heretofore referred to, which, from an operative standpoint in practical usage, possesses a high degree of efficiency and durability and which will be simple and inexpensive in mechanical construction.

50 The apparatus is so designed that the flow of ingoing oil and steam and the discharge

of distillates and generated gases may be continuous, and as the apparatus is arranged for such operation the lighter vapors will be 55 automatically separated from the heavier matter and the precipitation of the latter is provided for until it becomes necessary for its removal, while the heavier unconverted oils may be continuously returned to the converter for re-treatment.

The single figure of the accompanying drawing is a partially sectional diagram of apparatus arranged and constructed in accordance with my invention and constituting 65 one embodiment thereof.

This drawing shows an apparatus capable of being operated on a commercial scale wherein the oil may be transformed in considerable quantities and while but one 70 converter is shown it is to be understood that two or more of such converters may be employed in a battery, the vapor and gas outlets from which may lead to the same condenser or to a series of condensers.

75 The oil supply tank from which the oil is supplied to the apparatus for the conversion process is designated A, and the oil passing from this tank A, through pipe 5, is forced by pump 40, through pipe 6 and precision feed valves 7, into heater B, where it is heated to or above its boiling point and preferably to a temperature above 600° F., within the coils 8 of this heater. This hot oil is then admitted through pipe 9, to the 80 spray nozzle 10, located at one end of the mixing chamber 11.

Oil is admitted to the tank A, through pipe 1, controlled by valve 2, and displaced air may escape through pipe 3 controlled by 85 valve 4, when the tank is filled at first, but subsequently, and during the operation of the apparatus oil may be forced in through pipe 1, at greater pressure than that maintained by compressed air over the surface of 90 contained oil; such compressed air being furnished from an outside source through pipe 3 controlled by valve 4, but in such arrangement the pump 40, pipe 41 and valve 42 are omitted.

100 A gauge or set of glass gauges 12, may be arranged on tank A, to indicate the height of oil therein for when the apparatus is in operation the tank should be well filled with

oil and kept full in order to maintain a generous supply of the raw material undergoing transformation.

For the greater accuracy in delivering oil 5 into the system under a uniform pressure, the suction and force pump 40, is provided and interposed in the supply line 5-6, and which pump draws the oil from tank A, forces it against a back pressure into the 10 converter C-D-E, through the precision valves 7, heating coils 8, pipe 9 and nozzle 10.

As it is not possible to so perfectly regulate the speed of a pump as to accurately 15 deliver a given amount of oil into the converter, at all times and at a given pressure, a pipe 41 and an enclosed release or pop valve 42, are provided to return any excess oil to tank A, so that in this operation only 20 the desired amount of oil may pass into the converter as regulated by the precision valves 7:

In this manner, oil to be delivered into the system against a back pressure of say 25 75 pounds to the square inch will be forced by the pump 40, against the release valve 42, set at 100 pounds pressure, and in such regulation the oil will be delivered into the system under a head pressure of 25 30 pounds to the square inch above the 75 pounds maintained pressure, or sufficient to become properly atomized by the admixture of super-heated steam.

The oil preheater B, may be of any 35 suitable form such as a feed water heater, a small boiler or the like whereby the oil may be heated by suitable means in order to raise it in temperature, preferably above 600° F., within the coils 8, or sufficient 40 to become easily vaporized, cracked and transformed when brought into contact with high temperature super-heated steam through the nozzle 10, and within the mixing chamber 11 of the converter C-D-E.

45 Steam which may be generated in a boiler J, outside this converting apparatus and system is supplied through pipe 14 controlled by valve 15, to a trap 16 where any heavy steam is caught; then the dry steam 50 passes through pipe 17 into the superheating coils 18, of the heater B, is raised in temperature above 800 to 1000° F., and then flows through pipe 19 being mingled with and atomizing the heated oil as both oil 55 and steam pass through nozzle 10. The oil molecules are thus broken up and transformed from the high boiling oil into lower boiling products within the mixing chamber 11 and expander D.

60 In this form of heater, gas, fuel oil or other means may be employed by arranging a burner at the lower part of the enclosure containing the heater tubes, as shown, and providing a flue or vent leading to a stack 65 46, the flow of hot gases within which can

be controlled by a flue damper, as indicated in the drawing just above the top of the super-heater.

The steam generated in boiler J, must have a sufficiently high pressure to be forced into the converter C-D-E, in association with the oil admitted at 25 pounds head above the maintained back pressure and consequently the steam should have an equal pressure or 100 pounds to the 75 square inch, and which pressure can be recorded on the gauge 13, located at the top of the dry steam dome on the boiler J, while the oil pressure is recorded on the gauge 13', which gauge may be located 80 somewhere along the pipe 41, leading surplus oil to supply tank A.

Both the oil and steam may be controlled in its flow through nozzle 10, by valves 9' and 19', for the better regulation 85 and proportionate admission of steam and oil into the chamber 11 and expander C.

Located within the expander C, and opposite the mixing chamber 11, a curved plate 20, of metal such as hardened steel, 90 nickel, hard alloys or other substances capable of withstanding high temperatures, is made fast at an angle so as to deflect the incoming spray or vaporous oil in an upwardly direction towards the perforated disks 21, located in dome E, through 95 which the lighter converted vapors will rise and pass through pipe 25, into the condenser F.

Arranged between the expander C and 100 dome E, and connecting both of these parts, a tubular heater or cracking tube 22 is enclosed within a furnace D. This heater is preferably of tubular construction and can be made up of one or more tubes extending vertically through the furnace, the same being maintained at cracking temperatures, so that the incoming mingled oil and steam vapors may be kept at high temperatures while expanding in order to obtain thereby 105 the greatest yield of the desired low boiling products, and in order also to further decompose such oily vapors which may have escaped the action of the high temperature super-heated steam during its co- 110 mingling in the chamber 11.

The furnace D, is preferably composed of a steel shell lined with fire brick having insulating material between the shell and lining for confining the heat, and any suitable means may be provided for causing the heat in this chamber, such as burners supplied by fuel and air pipes 23 and 24, to consume gas or fuel oil or the heating can be done by any other economical means of 115 heat generation, the exhaust from which is carried through flue 47 to stack 46.

For economy and high efficiency, I prefer making the super-heating coils in tubular form so that there will be a large heating 130

surface presented as compared to the volume of oil and steam passing through them.

The heater B, is intended only to heat the oil sufficiently to cause its easy volatilization when admitted to the mixing chamber 11 and expander C, and is not intended to perform any cracking operation beyond that which might naturally take place in the more or less rapid passage of oil through the tubes while being subjected to high temperatures and pressures preparatory to their entering the nozzle 10, and becoming mixed with the super-heated steam to immediately vaporize and expand them for the vapor conversion process.

The construction of the heater B, is such that oil and oily vapors, after being subjected to the high temperature in the coils 8, pass out through the nozzle 10, and into the chamber 11, and then into the expanding receptacle C, where the lighter converted vapors rise and flow through chamber or cracking tube 22 to the dome E and the perforated baffle plates 21, and then pass out from the top of dome E through the pipe 25 to the coils 26, of the condenser F.

It will be noticed that the condenser F, is in free communication with the expander, heating tube and dome C—D—E, and that any pressure maintained in the apparatus C—D—E, will extend through the condenser F, as well.

The heavier unconverted vapors coming in contact with the perforated baffle plates 21, and being thrown down will be affected by the high temperature of the cracking tube 22, and a large part of such vapor may be broken up under the influence of this heat and the maintained pressure into finer vapors to again pass into the dome E and through the perforated plates 21, on their way to the condenser F.

In order to prevent any quantity of unconverted vapors that may have passed the baffle plates 21, entering the condenser F, a trap 48 is interposed in the vapor line 25, and a pipe 49 leads any heavy parts of oil from this trap to the discharge or overflow pipe 36 and into tank H, from which the oil may be withdrawn and passed through the converter again for re-treatment.

From the condenser, the distillates of condensation pass freely into a trap tank G, through pipe 27, and from which they may be withdrawn through pipe 28 controlled by valve 29, while the fixed gases generated during the operation of the process in this apparatus may escape through pipe 30 controlled by needle valve 31.

The vapor pressure in the system may be recorded on gauge 32, located at the top of trap tank G and on gauge 33 located on the tank H. By means of the needle valve 31 and the withdrawal of both liquid and gases from tank G, a constant predetermined va-

por pressure may be maintained within the system from the source of supply through to the foot of and beyond the condenser F.

Since some of the unconverted heavier vapors may fall to the bottom of the apparatus C—D—E, they will pass into the heavy bottoms chamber 34, located below the expander C, and in their passage they will carry any particles of coke or carbon which may result from the transformation process as carried on in this apparatus, and which may fall or precipitate to the lower part of the chamber C.

Such carbon or foreign solid matter which may be caught in this chamber 34, can be removed from time to time as occasion requires through the bottom of the chamber 34 by suspending operation, withdrawing oil from the converter, removing the cap plate 35 and clearing out the chamber; then replacing the cap and proceeding with the operation of the apparatus, the lighter part of the sediment may occasionally be withdrawn through pipe and valve 50, located near the lower end of the trap.

Any accumulation of hot oil in this chamber 34 will overflow through pipe 36 into the tank H, from which it can be removed as required through pipe 37 controlled by a valve.

Both the distillate tank G and hot oil overflow tank H, are provided with glass sight gauges 38 and 39, so that the operator may be informed as to when it is necessary to withdraw oil to make room for that which will be constantly flowing into these tanks.

The continual feeding of new quantities of hot oil to be broken into spray or vapors on admission to the mixing chamber 11 and expander C, together with the super-heated steam and the tendency of the super-heated oil to greatly expand when released, will build up or raise the vapor pressures in the converter and consequently throughout the condenser, so that the vapors undergoing the cracking operation will at all times be under super-atmospheric pressures while being subjected to the cracking heats of the steam and possibly also the external heat maintained at cracking temperatures in the cracking tube 22, provided for this purpose, and consequently the expander, heater and dome must necessarily be constructed of material sufficiently strong and enduring to withstand the required pressures and temperatures for protracted periods of time.

While the pressure gauges 32 and 33, register the vapor pressures in this form of apparatus, the gauge 13' in the oil line 41, should register a higher pressure by 10 to 25 pounds to the square inch so that the inflowing oil to the system will be fed at 10 to 25 pounds head pressure over the back or vapor pressure maintained in the system, otherwise the atomizing effect of the oil with

super-heated steam would be lost and the efficiency of the process as carried on in this apparatus would be rendered ineffective.

As the overflow hot oil may accumulate 5 rapidly in the operation of a battery of converters the pump 43 is connected with the tank H, and the oil may be intermittently or continuously withdrawn through pipe 37 and returned to the supply tank A, 10 through pipe 44.

As a means of safety in this high temperature and pressure apparatus a release blow off or pop valve 45, is preferably located at a distance away from the converter, usually 15 at the end of the vapor line 25, and just above the condenser E, as indicated in the drawing.

This valve may be set for a number of pounds above the actual working pressure 20 maintained in the system so that should any unusual pressure occur a means of releasing it, other than the bursting of some working part, will be interposed in the piping of the system.

25 This apparatus is, of course, not limited to the particular arrangement of parts shown in the drawing as the co-related parts may be combined in various ways to obtain the same process results but I believe the fundamental apparatus as set forth to be broadly new and it is my intention to cover the apparatus in its broadest aspect by the language employed in the following claims.

Having described my invention what I 35 claim as new and desire to secure by Letters Patent is:

1. An oil converting apparatus comprising an expansion chamber having spaced chambers with a communicating passage, 40 means for imparting heat to the communicating passage, a nozzle adapted to discharge into one of the chambers, an oil heating coil and a steam superheating coil connected to the nozzle, means for heating the coils so 45 that the oil is vaporized and largely cracked by the direct action of the superheated steam as it is discharged from the nozzle into one of said chambers, a condenser in open communication with the expansion chamber and 50 means for maintaining super-atmospheric pressure through the expansion chamber and condenser.

2. An oil converting apparatus comprising an expansion chamber having spaced 55 chambers with a communicating passage, means for imparting heat to the communicating passage, a nozzle adapted to discharge into one of the chambers, an oil heating coil and a steam superheating coil connected to the nozzle, means for heating the coils so 60 that the oil is vaporized and cracked as it is discharged from the nozzle with the superheated steam, a condenser in open communication with the expansion chamber, a collector connected to the condenser, a back 65

trap connected between the condenser and the expansion chamber and means for returning the liquid from the back trap to the oil heating coil.

3. An oil converting apparatus comprising 70 an expansion chamber having spaced chambers with a communicating passage, means for imparting heat to the communicating passage, a nozzle adapted to discharge into one of the chambers, an oil heating coil 75 and a steam superheating coil connected to the nozzle, means for heating the coils so that the oil is vaporized and largely cracked by the direct action of the superheated steam as it is discharged from the nozzle into one 80 of said chambers, a condenser in open communication with the expansion chamber, a collector in open communication with the condenser, and means for maintaining super-atmospheric pressure through the expansion 85 chamber, the condenser and the collector.

4. An oil conversion apparatus comprising 90 an expansion chamber, having spaced upper and lower chambers and an interposed communicating passage, means for spraying into the lower chamber a mixture of hot oil and steam superheated to sufficient temperature to largely crack the oil by its direct action as it is commingled therewith, in said lower chamber, means for imparting a cracking heat to said communicating passage to augment the cracking process as the vapors rise therethrough and means for withdrawing the evolved vapors from the upper chamber.

5. An oil conversion apparatus comprising 95 an expansion chamber having an enlarged mixing chamber projecting laterally therefrom, a spraying nozzle mounted in the outer end of said mixing chamber and discharging through said mixing chamber a baffle plate against which the mixed vapors are projected and into said expansion chamber and means for supplying to said nozzle hot oil and steam superheated to sufficiently 100 high temperature to crack the oil by its direct action as it is mixed therewith in said expansion chamber.

6. An oil conversion apparatus comprising 110 an expansion chamber, means for spraying into said chamber a mixture of hot oil and steam superheated to a sufficient temperature to produce cracking by its direct action as it is commingled therewith in said chamber, means for collecting the heavy residue below the cracking zone of said chamber, means for withdrawing the evolved vapors and condensing them and means for back trapping the unconverted vapors and the heavy residue and returning them to said 115 spraying means.

7. An oil conversion apparatus comprising 120 a vertically arranged elongated expansion chamber, an atomizer for laterally spraying into the lower part of said chamber 125

a mixture of hot oil and steam superheated to a sufficient temperature to produce cracking by its direct action as it is commingled therewith in said chamber, a receiver disposed below said chamber and outside the cracking zone for collecting the heavy residue, means for withdrawing the residue from said receiver, and means connected to the

top of said chamber above the cracking zone for removing the evolved vapors.

In testimony whereof I affix my signature.

JOSEPH H. ADAMS.
